UNITED STATES PATENT OFFICE.

WILLIAM GEARKE, OF LORAN, ILLINOIS.

SWINGING GATE.

SPECIFICATION forming part of Letters Patent No. 248,304, dated October 18, 1881.

Application filed June 16, 1881. (Model.)

To all whom it may concern:

Be it known that I, WILLIAM GEARKE, of Lorran, in the county of Stephenson and State of Illinois, have invented certain new and useful Improvements in Swinging Gates; and I do hereby declare that the following is a full, clear, and exact description of the invention, which will enable others skilled in the art to which it appertains to make and use the same, reference 5 being had to the accompanying drawings, which form a part of this specification.

Figure 1 is a side view of my improved gate. Fig. 2 is a vertical sectional view, and Fig. 3 is a horizontal sectional view on the line *x x*. Corresponding parts in the several figures 15 are denoted by like letters of reference. This invention relates to swinging gates; and it consists in certain improvements of the same, which will be hereinafter fully described, and 20 particularly pointed out in the claim.

In the drawings hereto annexed, A represents the base or sill of my improved gate, which is provided at its ends with uprights or posts B C, the former of which is the main gate- 25 post. The said post B is provided near the base with an approximately circular ring or casting, D, having beveled sides E. At its upper end the post B is provided with a laterally-projecting bracket, F, having a perforation, G, 30 which forms a bearing for the upper spindle of the gate.

The lower side of the ring or casting D has a transverse cross-bar, H, with a perforation, I, which forms a bearing for the lower spindle 35 of the gate.

The gate, which is indicated by letter J, may be constructed in any suitable manner. The end post, K, is provided with pins or spindles L M, fitted in the bearings G I, and at the 40 lower end of said post K, between it and one of the pickets N, is journaled a roller or caster, O, traveling upon the beveled sides or tracks E of the casting D.

The roller O is journaled on the shaft S, having bearings in the picket N and metallic plate N', secured to end post, K, between a shoulder,

s, thereon and an adjusting-pin, a, by means of which it may be laterally adjusted, aided by the insertion of washers between the roller and shoulder, to suit the contraction and expansion 50 of the metallic track in different seasons.

The post P, at the free or swinging end of the gate, is provided with a gravity-latch, Q, engaging a double catch, R, upon the inner side of the end post, C.

The operation of my invention will be readily understood. The gate may swing open to either side, and will, when opened, be raised or lifted to a certain extent by the caster O traveling upon the inclined tracks E. When 60 the gate is released its weight will cause it to swing back automatically until closed by the gravity-latch Q engaging the double catch R.

My improved gate is simple, convenient, inexpensive, and easily operated.

I am aware that it is not new to construct a gate with a roller traveling upon an inclined track, and such I do not claim, broadly, as of my invention.

Having thus described my invention, I claim 70 and desire to secure by Letters Patent of the United States—

As an improvement in gates, the combination, with the beveled circular ring or casting D E, of the gate J, having the shaft S journaled 75 between the end piece, K, and adjoining picket N at the bottom, said shaft being provided with a shoulder, s, and an adjusting-pin, a, between which is journaled the roller O, and by means of which the roller is laterally adjustable to suit the expansion and contraction of the ring D, all arranged and operating substantially as and for the purpose herein shown and specified.

In testimony that I claim the foregoing as 85 my own I have hereto affixed my signature in presence of two witnesses.

WILLIAM GEARKE.
